UNITED STATES PATENT OFFICE.

JULES J. SARRAZIN, OF NEW ORLEANS, LOUISIANA.

TOOTH-BRUSH.

1,048,740.

Specification of Letters Patent. Patented Dec. 31, 1912.

Application filed October 25, 1911. Serial No. 656,647.

To all whom it may concern:

Be it known that I, JULES J. SARRAZIN, a citizen of the United States, residing at New Orleans, in the parish of Orleans and State 5 of Louisiana, have invented certain new and useful Improvements in Tooth-Brushes, of which the following is a specification.

This invention has for its object to provide in a tooth brush a novel arrangement 10 of brush head and bristle tufts so as to enable the brush to be easily operated, and to perform functions very difficult to and usually missed with full bristled brushes.

In the accompanying drawing—Figure 1 15 is a perspective view of the brush; Fig. 2 is an end view thereof, and Fig. 3 is a side elevation.

Referring specifically to the drawing, 5 denotes the handle of the brush. From each 20 end of the handle extends a narrow, elongated neck 6 which is formed at its extremity into a head. The head 7 of one neck is provided with bristle tufts 8 which extend outwardly from said head in a line substantially 25 parallel to the longitudinal axis of the handle, the arrangement being similar to an ordinary paint brush. The head 9 of the other neck is of greater width than length and carries bristle tufts 10 which are 30 arranged in rows extending transversely of the head. The tufts extend at substantially right angles to the handle, similar to the blade of a hoe. Two rows of tufts are shown, but the number of rows may be 35 varied, provided they are arranged as shown, to form a short, moderately wide group of long tufts extending transversely of the brush head. The tufts of the respective rows are in alinement, and in the extremity of each tuft is made a V-shaped recess 40 11 extending in the direction of the length of the brush handle. The recesses of the tufts of the respective rows are in alinement whereby V-shaped grooves are formed 45 in the group of tufts, said grooves extending in the direction of the longitudinal axis of the brush handle. The outer surface of the group of tufts is thus given a serrated or zig-zag outline. The dividing lines between the 50 tufts in each row intersect the apices of the serrations, as clearly shown in Fig. 2. This particular arrangement of the serrations is important and is designed to overcome the objection in brushes having their serrations 55 formed by trimming off the tufts on the sides to form grooves between the tufts.

Brushing vertically, from the gums to the incisal edges, lingually of lower incisors, the ordinary trimming would cause the tufts to part from one another as they reached the 60 necks of roots and teeth, penetrating between the teeth, but failing to give proper friction just at the lingual convexity of the necks, where it is so necessary. By trimming right into the center of the tufts, in 65 accordance with the present invention, the shorter bristles at the center of the tufts come into play on the lingual convexity of necks at the same time that the edges of tufts formed by the long bristles penetrate 70 between the teeth. Again, the edge tufts are not completely spread out of action as with the ordinary trimming. A further advantage of cutting away the centers of the tufts to form the grooves or 75 serrations, is that the brush does better work on the distal necks of teeth next to gaps, both above and below, and on the distal necks of rearmost molars, because the bristles adapt themselves to such necks and 80 are forced against them, and they all remain in action, even the slanting outer edges of the side tufts, and the trimming encircles such necks, instead of causing the edge tufts to just glance away from them. Similarly, 85 when brushing abutments under bridges, the same advantage is gained as just explained, the extreme side tufts remaining in action, and their edges encircling the convex surfaces when all the bristles are forced against 90 them, instead of the extreme side tufts glancing away and off them as with the usual trimming. Furthermore, children, in 95 cleansing orthodontic bandages, require a style of trimming which properly catches on, around, and under wires and small lugs, instead of tufts which tend to spread apart as such small appliances get between them, the result being that the most effective part 100 of the tufts, which is the extremity of the bristles, ceases playing on them. This faulty condition is corrected by the herein-described trimming, the very extremity of the bristles being kept at work on small objects, since bristles thickly bunched together 105 are brought to bear as the depth of troughs are reached, instead of the tufts having a tendency to divide from each other as in the ordinary style of trimming when small objects come therebetween, at the same time 110 that friction behind them, at the gum line, is increased.

The brush herein described is adapted more particularly for cleaning behind the front teeth. In use, it is held and operated similar to a hoe, the handle being held in a 5 downwardly extending direction when cleaning the upper teeth, and in an upwardly extending direction when cleaning the lower teeth. By this method both the upper and lower rear surfaces of the front 10 teeth can be easily and thoroughly cleaned. By having the tufts extend at right angles to the handle, the brush can be readily operated behind the teeth and it will reach all 15 parts thereof and the adjacent tissues. The brush is invaluable behind the rearmost large molar teeth, both above and below, behind all side and back teeth which stand next to gaps whence teeth have been lost, whether in the upper or lower jaw, underneath 20 upper and lower front dental bridges (entering the bristles behind them), and against the anterior piers of both upper and lower side and rear bridges (the bristles reaching from inside of the mouth). The 25 brush is likewise invaluable for children to clean under and around bandages for straightening teeth. The serrations are important for the reason that as the bristles are rubbed from the gums toward the front 30 teeth, behind them, the convex portion of the teeth get friction, besides the bristles penetrating between the teeth. Brushing teeth crosswise, for many reasons well known to the dental profession, is the greatest error 35 possible, and the brush is devised for the bristles to work from gums to morsal sur-

faces, stimulating the circulation of blood, and at the same time doing the most effective and desirable cleansing.

The two necks 6 are bowed outwardly 40 from the handle portion 5, and the latter has an aperture 12 so that the brush may be hung up on a nail extending from a wall or other support, from which latter the brush head is spaced by bowing the necks as stated. 45 The two necks are curved toward the inside of the brush so as to facilitate the bristles reaching the above-mentioned localities.

I claim:

1. A tooth brush comprising a handle, a 50 head, and a group of bristle tufts carried by the head, the outer surface of the group being serrated, and the dividing lines between the tufts intersecting the apices of the serrations. 55

2. A tooth brush comprising a handle, a head, and bristle tufts carried by the head, said tufts being arranged in a relatively narrow group extending transversely of the head, and the bristles projecting outward 60 from the head at a right angle to the longitudinal axis of the handle, the outer surface of said group of bristles being serrated, and the dividing lines between the tufts intersecting the apices of the serrations. 65

In testimony whereof I affix my signature in presence of two witnesses.

JULES J. SARAZIN.
